LASTING MACHINE

Philip E. Burby, Beverly, Mass., assignor to United
Shoe Machinery Corporation, Flemington, N. J.,
a corporation of New Jersey

Application April 14, 1944, Serial No. 531,075

28 Claims. (Cl. 12—14)

This invention relates to lasting machines, and more particularly to the positioning of shoes in such machines. The invention is herein illustrated as applied to a power-operated toe-end lasting machine which, except as hereinafter noted, is constructed generally as disclosed in United States Letters Patent No. 2,160,846, granted on June 6, 1939, on an application of F. C. Eastman's and A. F. Pym's. It should be understood, however, that it is not limited to machine organizations of that particular character.

The machine shown in the above-mentioned Letters Patent is provided with wipers which are swung upwardly to a substantially horizontal plane to wipe the toe-end portion of an upper heightwise of a last positioned bottom upward, and are thereafter advanced and closed inwardly lengthwise and widthwise of the last to wipe the marginal portion of the upper over the feather and against the lip of a welt shoe insole on the last. The last and the shoe materials thereon, hereinafter sometimes referred to inclusively as the shoe, are positioned in proper relation to the wipers for the toe-lasting operation by a plate curved to engage the inner face of the lip of the insole about the end and along the sides of the toe and having a downwardly extending flange which engages the bottom face of the insole adjacent to the lip. By such engagement with the insole the plate determines in all respects the position of the shoe. That is, it positions it bodily heightwise, lengthwise and laterally, and also determines its position with respect to lateral swinging movement and with respect to lateral or longitudinal tipping movement. Not only is the plate curved to conform substantially to the curvature of the inner face of the lip of the insole, but its downwardly extending flange also is so shaped at its lower edge as to conform substantially to such curvature as there may be on the bottom of the toe end of the last and to cause the shoe to assume that position with respect to lateral and longitudinal tipping movements which will render the wipers most effective in wiping the upper inwardly over the feather of the insole all around the toe. To obtain satisfactory results, therefore, it is necessary to provide differently formed shoe-positioning plates for shoes of different styles and also different plates for right and left shoes respectively and for shoes differing substantially as to size. Three or four pairs of plates may thus be required for the usual run of sizes of a given style.

An object of the present invention is to provide a construction such that the same shoe-positioning means may be used for shoes of various styles and sizes and for right and left shoes, thus eliminating the need for the large numbers of specially formed plates required heretofore.

For the purposes in view, the construction herein shown comprises a pair of shoe-positioning members arranged to engage the inner face of the lip of the insole along the opposite sides of the toe respectively, and means for adjusting these members in various ways to meet different requirements. As illustrated, mechanisms are provided for adjusting the members bodily toward or from each other widthwise of the shoe, 5 for tipping them in unison heightwise of the shoe in accordance with the lengthwise curvature of the forepart of the shoe bottom, and for relatively adjusting heightwise of the shoe the portions of the members comparatively remote from the end of the toe in accordance with differences 10 in the bottom contours of right and left shoes respectively in some styles of shoes. Provision is also afforded in the construction shown for the members further to adjust themselves to some extent to the lip of each insole by turning about axes extending heightwise of the shoe. It is contemplated that after the members have been adjusted by the operator for a shoe of a given style, no change will ordinarily be required in operating on all shoes of that style except such of the 15 above-mentioned adjustments as may be needed for width or for rights and lefts. To assist the operator in making the proper adjustments for the first shoe of a given style, the invention further provides novel means for properly locating such a shoe in the machine while the shoe-positioning members are adjusted to it.

The above and other features of the invention, including various novel details of construction and combinations of parts, will now be more particularly described with reference to the accompanying drawings and thereafter pointed out in the claims.

In the drawings,

Fig. 1 is a view mainly in front elevation of a portion of a machine constructed generally as disclosed in the previously mentioned Letters Patent but modified for purposes of the present invention, a shoe being shown in section to illustrate how the first shoe of a given style is properly located in the machine for adjustment of the shoe-positioning means thereto;

Fig. 2 is a perspective view of a portion of the structure shown in Fig. 1;

Fig. 3 is a view partly in right-hand side elevation and partly in section, showing mainly the shoe-positioning means in its adjusted relation to a shoe;

Fig. 4 shows the shoe-positioning means partly in elevation and partly in section on the line IV—IV of Fig. 3;

Fig. 5 is a section on the line V—V of Fig. 1;

Fig. 6 is a view partly in plan and partly in section on the line VI—VI of Fig. 3; and

Fig. 7 is a section on the line VII—VII of Fig. 3.

As fully disclosed in the above-mentioned Letters Patent, the machine to which the invention is herein illustrated as applied is provided with a pair of toe-embracing wipers 2 which are swung upwardly from a somewhat inclined position to a substantially horizontal plane to wipe the toe-end portion of an upper heightwise of a last and are thereafter advanced and closed inwardly lengthwise and widthwise of the last respectively to wipe the marginal portion of the upper over the feather and against the lip of a welt shoe insole on the last. Arranged to cooperate with the wipers in the toe-lasting operation, in the construction herein shown, is a retarder 4 (Fig. 3) which clamps the margin of the upper outspread on the wipers, this retarder being constructed and operated as disclosed in a copending application of mine, Serial No. 485,577, filed on May 4, 1943 and being used in place of the grippers shown in the first-mentioned Letters Patent. In Fig. 3 the retarder is shown as it starts to release the margin of the upper just after the wipers begin their movements to wipe the upper inwardly over the insole.

For positioning a shoe in proper relation to the wipers such a machine has been provided heretofore with a plate formed to engage the inner face of the lip of the insole about the end and along the sides of the toe, as hereinabove explained, the plate being detachably supported on the lower end of a vertical rod 6 and the shoe being clamped against the plate by a toe rest 8 in the power operation of the machine. Instead of such a plate, the machine herein shown is provided, for purposes of this invention, with shoe-positioning means which will now be described. Arranged to engage the toe-end portion of the insole at the opposite sides of the toe respectively are two shoe-positioning members 10 spaced from each other widthwise of the shoe. These members are curved for engagement with the inner face of the lip of the insole, and they have relatively narrow downwardly extending flanges arranged to seat on the bottom of the insole adjacent to the lip as illustrated in Fig. 1. To allow for variations in curvature of the bottoms of shoes of different styles and sizes, the lower edge of each member is recessed between its opposite ends as shown at 12 (Fig. 4), so that it may have virtually a two-point bearing on the insole. Secured to each member is an upwardly extending pin 14 mounted in a holder 16 which overlies the member and is in contact therewith, this pin having between its ends a shallow annular recess 18 (Fig. 3) to receive the rounded end of a retaining pin 20 slidably mounted in the holder. A head on the other end of the pin 20 is engaged by a spring 22 held under compression by a screw 24 in the holder. Each member 10, therefore, may be readily detached from its holder 16 by a pull applied thereto in a downward direction, and it may be readily returned to its normal position by forcing the upper end of its pin 14 upwardly past the yieldable retaining pin 20. The manner in which each member 10 is thus mounted on its holder, moreover, permits some self-adjustment of the member to the lip of the insole, upon engagement of the lip therewith, by turning movement about the axis of the pin 14. To prevent any undue displacement of the member about this axis when

there is no shoe in the machine, the holder 16 is provided with a shoulder 26 arranged to be engaged by what may be termed the rear end face of the member, i. e., the end face thereof which is farthest from the end of the toe.

Pivottally connected by a pin 28 to the front end of each holder 16, i. e., the end thereof nearest the end of the toe, is a bar 30 extending upwardly through a slot 32 (Fig. 4) in a crossbar 34. Threaded in this crossbar is a sleeve 36 knurled at its upper end and rotatable about a vertical headed stud 38 which is threaded at its lower end in a shelf 40 projecting from the rod 6, the sleeve being supported at its lower end on this shelf and confined between the shelf and the head of the stud. Fast on each bar 30 is a collar 42 resting on the top of the crossbar 34. It will thus be seen that the front ends of the holders 16 are supported by the crossbar 34 and that by turning movement of the sleeve 36 the crossbar and these ends of the holders may be adjusted in unison heightwise of the shoe. To support these ends of the holders against the upward pressure of the shoe on the members 10, shoulders 44 formed on enlarged portions of the bars 30 are engaged by the lower face of the crossbar 34.

Pivottally connected by a pin 46 to the rear end of each holder 16 is a bar 48 extending upwardly through a block 50 which is mounted to slide in directions widthwise of the shoe on an arm 52 extending from the rod 6 in fixed relation thereto, the block having therein a T-shaped slot to receive a correspondingly shaped portion of the arm. Fixed in the upper end of each bar 48 is a stem 54 extending downwardly from a small block 56 having therein a slot 60 extending widthwise of the shoe. Lying in the two slots 60 are pins 62 mounted respectively on the opposite ends of a lever 64 which is pivotally mounted midway between its opposite ends on a headed stud 66 threaded in a bar 68 extending upwardly from another arm 70 (Fig. 5) on the rod 6. The purpose and function of the lever 64 will be more particularly hereinafter described. It will be noted that through the pins 62 and the bars 48 this lever supports the rear ends of the holders 16 on which the shoe-positioning members 10 are supported.

Also mounted to slide along guideways on the arms 52 are blocks 72 having lugs 74 (Fig. 5) extending into recesses in the blocks 50, so that each block 72 and the block 50 associated therewith are interlocked for movement as a unit in directions widthwise of the shoe. Each block 72 is provided with a pair of arms 76 and 78 through holes in which the bar 30 at the same side of the mechanism extends. By movements of the blocks 50 and 72 along the arms 52, therefore, the holders 16 for the shoe-positioning members 10 may be adjusted bodily toward or from each other widthwise of the shoe. Movements of the same extent are imparted simultaneously to the two blocks 50 and to the blocks 72 connected thereto by a pinion 80 formed on a shaft 82 which is rotatable in a bushing 84 (Fig. 5) in the arm 70, this pinion being engaged above by a rack bar 86 (Fig. 1) extending from one of the blocks 50 and engaged underneath by another rack bar 88 extending from the other block 50. A hand wheel 90 fast on the shaft 82 serves as means for turning the pinion, the latter being held in place by a cover plate 92 on the arm 70 engaging the outer end of the bushing 84. To afford better insurance that after the holders 16 have been

adjusted by this mechanism they will not be displaced widthwise of the shoe by pressure against the shoe-positioning members 10, a spring washer 94 is inserted between the hub of the hand wheel 90 and the cover plate 92 to act frictionally on the hand wheel and the cover plate.

To determine invariably the positions of shoes lengthwise in the machine, there is mounted centrally between the portions of the members 10 which are located at the end of the toe another shoe-positioning member 96 in the form of a vertical finger secured at its upper end to the vertically adjustable crossbar 34. This finger is arranged to engage the inner face of the lip of the insole at the extreme end of the toe and is beveled on its lower end face to facilitate its engagement with the bottom face of the insole close to the lip.

In order to indicate to the operator the condition of the mechanism with respect to vertical adjustment of the front ends of the holders 16 by the threaded sleeve 36, there is provided a gage member 98 having a substantially horizontal portion supported on a shoulder on one of the bars 30 and an upwardly extending portion guided in a recess formed in a plate 100 fast on one of the blocks 72. It will be understood that when adjustment is effected by turning the sleeve 36 the gage member will move upwardly or downwardly with the bar 30 on which it is supported. Extending upwardly from the plate 100 is an indicator 102 the upper edge of which is arranged to align with the marks of a scale on the gage member.

In order to position in proper relation to the wipers the toe end of a shoe made on a last having a convex face on the bottom of its forepart, it is usually necessary that the rear end of that member 10 which engages the insole at the inner side of the shoe bottom shall be slightly lower than the rear end of the other member because of a more pronounced curvature on the corresponding portion of the bottom of the last. This consideration as to the shape of the last is one which has been taken into account in forming the shoe-positioning plates used heretofore. It is for the purpose of thus positioning the rear ends of the members 10 in proper relation to each other and of quickly reversing their relative positions for right and left shoes respectively that the bars 46 supporting the rear ends of the holders 16 are connected at their upper ends to the previously mentioned lever 64. This lever has integral therewith an upwardly extending arm 104 provided with a slot 106 (Fig. 1) in which lies a slide 108 (Figs. 3 and 7), the slide having integral therewith a round knob 110 lying in a triangular opening 112 in the bar 68. Extending from the slide 108 is a pin 114 on which is slidably mounted a sleeve 116 provided with a vertical slot into which the slide 108 extends. At the opposite sides of the slide the sleeve 116 has sharp edges 117 (Fig. 7) arranged to extend into pairs of slots 118 (Fig. 1) in the arm 104 to hold the knob 110 at different heights in the triangular slot 112. A spring 120 compressed between a shoulder on the sleeve 116 and the head of a screw 122 threaded in the pin 114 holds the sleeve normally with its edges in a pair of the slots but permits them to be withdrawn from the slots when it is desired to adjust the knob 110 upwardly or downwardly. Opposite the pairs of slots are numbers on the arm 104 to indicate different adjusted positions of the knob. It will be understood that the knob, by its en-

gagement with the downwardly converging walls of the opening 112 in the bar 68, limits the movements of the lever 64 and therefore the relative vertical movements of the rear ends of the shoe-positioning members 10. When the knob is positioned at the proper height for a particular style of shoe, all that is necessary in changing from a right to a left shoe or vice versa is to swing the arm 104 in the proper direction until it is stopped by engagement of the knob 110 with a wall of the opening 112. To hold the arm in adjusted position it carries at its upper end a pin 124 extending through a curved slot 126 in the bar 68 and having a head 128 in engagement with the bar, the pin having threaded thereon a nut 130 for clamping the bar and the arm 104 together. A small pin 132 extending from the pin 124 into a slot in the arm 104 prevents the pin 124 from turning.

From the foregoing description it will be seen that by turning the hand wheel 90 the members 10 may be adjusted bodily toward or from each other for shoes of different widths, that by turning the sleeve 36 the members may be swung upwardly or downwardly in unison about the pins 46 in accordance with the lengthwise curvature of the bottom of the forepart of the shoe, and that by swinging the arm 104 the rear ends of the members may be relatively adjusted heightwise of the shoe by swinging the members about the pins 28. The members may be further adjusted bodily heightwise of the shoe, as may be required by the thickness of the upper materials or to compensate for their adjustment about the pins 46, by means provided heretofore in the machine to which the invention is shown as applied for vertically adjusting the rod 6. This means comprises a sleeve 134 rotatable on a reduced upper end portion of the rod and confined thereon by a nut 136, the sleeve being threaded in a frame casting 138 and being provided with a hand wheel 140 for turning it. A pointer 142 on the frame casting is arranged to indicate by reference to numbers on the hand wheel the position of the rod with respect to adjustment. Turning of the rod is prevented by a key 144 extending from the frame casting into a slot in the rod.

It is contemplated that the shoe-positioning members 10 will be preliminarily adjusted in the manner described with reference to a shoe of a given style on which the machine is to operate, and that thereafter ordinarily no further adjustment will be required in operating on shoes of that style except in some instances an adjustment through the arm 104 for rights and lefts and occasionally an adjustment for width by the turning of the hand wheel 90. To serve as a guide in such preliminary adjustment of the members the first shoe of the given style will preferably be presented in the position which it is to occupy in the toe-lasting operation, except that its toe end need not be accurately positioned laterally since the members 10 will properly position it in this respect when they engage the lip of the insole. Its proper position lengthwise will be determined by engagement of the central positioning member 96 with the lip of the insole at the end of the toe. To locate the shoe properly in other respects for purposes of adjustment of the shoe-positioning means, the machine herein shown is provided on the front of the frame with a pair of arms 146 each supported on a pin 148 which extends from the frame through a slot 150 in the arm and has threaded thereon a thumb nut 152 for clamping and holding the arm either

in an idle position, such as indicated by broken lines with reference to one of the arms in Fig. 1, or in what may be termed an operative position in which each arm is shown in full lines in that figure. The operative position of each arm is further determined by another pin 154 in the frame on which the arm rests. Mounted on each arm is a holder 156 which supports a plurality of fingers 158, herein shown as four in number, portions of the fingers extending into a slot 160 in a split portion of the holder and being clamped therein by a plurality of screws 162 which tend to contract that portion of the holder. The holder may be adjusted vertically along a guideway on the arm and is held in adjusted position by a clamping screw 164 extending through a slot 166 in the arm. Downwardly extending portions of the fingers 158 have lower end faces arranged to engage the feather of the insole along the opposite sides of the toe and thereby to determine the position of the shoe heightwise and with respect to lengthwise or lateral tipping movements. These end faces of the fingers, when the arms 146 are in their operative positions, all lie in a plane which is substantially parallel to the plane of the wipers when the latter are in positions for wiping the marginal portion of the upper inwardly over the insole, but may be somewhat below the plane of the wipers in view of the thickness of the upper materials to be wiped inwardly. Vertical adjustment of the holders 156 relatively to the arms 146 is essentially a setting-up adjustment and ordinarily need not be changed, since vertical adjustment of the shoe-positioning means to accommodate it to various thicknesses of upper materials may be readily effected at any time by the hand wheel 140. It will be understood that the screws 162 may be loosened and that the fingers 158 may be adjusted toward or from each other or in inward or outward directions to adapt them best for the style or size of shoe presented to them, and also that, if desired, some of the fingers may be removed. Preferably they will be so adjusted as not to engage the outer face of the lip of the insole, thus affording leeway for the proper positioning of the shoe laterally by outward movements of the members 10. The manner in which the members 10 are further adjusted to the shoe positioned by the fingers 158, by turning movements of the sleeve 36 and the hand wheel 140, will be fully understood from the description already given. To effect the relative vertical adjustment of the rear ends of the members the operator loosens the nut 130 and swings the arm 104 in the proper direction as far as determined by the shoe. He then adjusts the slide 108 downwardly along the slot 160 until its knob 110 engages the bar 68 at one side of the opening 112 in the bar. The slide is then held in adjusted position by engagement of the edges 117 of the sleeve 116 with the arm 104 in one of the pairs of slots 118, the pairs of slots being spaced from one another distances which correspond to adjustments of only about $\frac{1}{2}$ of an inch of the rear ends of the members 10. After making this adjustment the operator tightens the nut 130 again. It will be understood that thereafter, in changing from a right to a left shoe or vice versa, the appropriate adjustment of the arm 104 will be made merely by swinging it in one direction or the other as far as permitted by engagement of the knob 110 with the bar 68 at one side or the other of the opening 112, the nut 130 being tightened after each adjustment.

After having adjusted the shoe-positioning means as above described in accordance with the style of shoe on which the machine is to operate, the operator returns the arms 146 to their idle positions and is then ready to use the machine in lasting shoes of that style. He may, moreover, make a note of the readings on the gage member 98, the arm 104, and the hand wheel 140, indicating the proper adjustments for that style of shoe, and thereafter need only make adjustments in accordance with these readings in case he should return to that style of shoe after having in the meantime adjusted the machine for a different style.

15 Instead of using the arms 146 and their fingers 158 to assist in determining the position of a shoe when the operator adjusts the shoe-positioning means to the shoe as above described, he may use the wipers 2 for that purpose after 20 having operated the machine by hand to bring the wipers into the positions which they occupy in wiping the upper inwardly over the insole. In that case it may be more convenient, instead 25 of presenting to the wipers a shoe which is ready for toe lasting, to present a last having only an insole thereon, the last being so positioned that the wipers will engage the feather of the insole at the end and the sides of the toe. Such a last and insole only may likewise be used when the 30 fingers 158 are to serve as the locating means.

In using the machine to last shoes after having properly adjusted the shoe-positioning means the operator will present each shoe first in a position where the central lip-engaging member 96 is spaced somewhat from the lip of the insole and will then move the shoe lengthwise in a heelward direction until this member properly engages the lip. As the shoe is thus moved the members 10 may adjust themselves better 40 to the lip of the insole by turning about the axes of the pins 14. These members are so shaped as to conform ordinarily with sufficient accuracy to the lip of the insole in operating on shoes of different styles and sizes and on right and left shoes. For wide differences in style, however, 45 differently shaped members may be required, the members being readily detachable from their holders 16, as fully explained, to permit different members to be substituted.

Having described the invention, what I claim as new and desire to secure by Letters Patent of the United States is:

1. In a lasting machine, the combination with 55 wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole at the opposite sides of the toe respectively, and means for adjusting said members bodily widthwise of the shoe relatively to each other and for retaining them in adjusted 60 positions for use on a plurality of shoes.

2. In a lasting machine, the combination with 65 wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole at the opposite sides of the toe respectively, and adjusting means including an 70

adjusting member common to said shoe-positioning members for simultaneously adjusting them bodily equal distances toward or from each other widthwise of the shoe.

3. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole at the opposite sides of the toe respectively, said members being bodily movable relatively to each other widthwise of a shoe presented to the machine into engagement with the lip of the insole at the sides of the toe, and means for retaining said members in the positions thus determined by the lip for use on a plurality of shoes.

4. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole at the opposite sides of the toe respectively, said members being bodily movable relatively to each other widthwise of a shoe presented to the machine into engagement with the lip of the insole at the sides of the toe, and means for retaining said members in the positions thus determined by the lip for use on a plurality of shoes.

5. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole at the opposite sides of the toe respectively, blocks connected to said members and mounted to slide in directions widthwise of the shoe to adjust the members toward or from each other, and rack-and-pinion mechanism for thus moving said blocks.

6. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole at the opposite sides of the toe respectively, holders supporting said members, bars arranged to extend heightwise of the shoe and connected to said holders for supporting them, and means arranged to act through said bars to adjust said holders relatively to each other widthwise of the shoe.

6. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole along the opposite sides of the toe respectively and bodily adjustable relatively to each other widthwise of the shoe, and another shoe-positioning member arranged to engage the inner face of the lip at the end of the toe between said first-named members.

7. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole along the opposite sides of the toe respectively and bodily adjustable relatively to each other widthwise of the shoe, and means for retaining said

members in their adjusted positions for use on a plurality of shoes, said members being so mounted as to permit them further to adjust themselves to the lip of the insole each about an axis extending heightwise of the shoe upon presentation of each shoe to the machine.

5 8. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole along the opposite sides of the toe respectively, a pair of holders supporting said members, and means for adjusting said holders relatively to each other widthwise of the shoe and for retaining them in their adjusted positions, said members being mounted on their holders for swinging movements each about an axis extending heightwise of the shoe to permit them further to adjust themselves to the lip of the insole upon presentation of each shoe to the machine.

20 9. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole along the opposite sides of the toe respectively and also to engage the bottom of the insole adjacent to the lip, said members being bodily adjustable relatively to each other widthwise of the shoe and also adjustable angularly heightwise of the shoe each about an axis extending widthwise of the shoe, and means for retaining the 30 members in their adjusted positions.

40 10. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole along the opposite sides of the toe respectively and also to engage the bottom of the insole adjacent to the lip, means for adjusting said members bodily widthwise of the shoe relatively to each other, and additional means for adjusting them angularly heightwise of the shoe each about an axis extending widthwise of the shoe.

50 11. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole along the opposite sides of the toe respectively and also to engage the bottom of the insole adjacent to the lip, holders supporting said members and arranged to extend lengthwise of the shoe opposite the forepart of the shoe bottom, means for adjusting said holders toward or from each other widthwise of the shoe, and additional means connected to portions of said holders located comparatively near the end of the toe for adjusting them heightwise of the shoe each about 60 an axis extending widthwise of the shoe and lo-

cated comparatively remote from the end of the toe.

12. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole along the opposite sides of the toe respectively and also to engage the bottom of the insole adjacent to the lip, holders supporting said members and arranged to extend lengthwise of the shoe, different pairs of bars arranged to extend heightwise of the shoe and pivotally connected respectively to the opposite end portions of said holders, means arranged to act through said bars to adjust the holders toward or from each other widthwise of the shoe, and means connected to one of said pairs of bars for adjusting said holders angularly heightwise of the shoe about their pivotal connections with the other pair of bars.

13. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole along the opposite sides of the toe respectively and also to engage the bottom of the insole adjacent to the lip, said members being adjustable relatively to each other widthwise of the shoe and further adjustable rectilinearly heightwise of the shoe and also angularly each about an axis extending widthwise of the shoe, and means for retaining the members in their adjusted positions.

14. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole along the opposite sides of the toe respectively and also to engage the bottom of the insole adjacent to the lip, means for adjusting said members toward or from each other widthwise of the shoe, additional means for adjusting the members rectilinearly heightwise of the shoe, and still other means for adjusting them angularly heightwise of the shoe each about an axis extending widthwise of the shoe.

15. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole along the opposite sides of the toe respectively and also to engage the bottom of the insole adjacent to the lip, said members being adjustable relatively to each other widthwise of the shoe, means for adjusting said members also in unison heightwise of the shoe each about an axis located opposite the bottom of the shoe comparatively remote from the end of the toe, and additional means for further adjusting the mem-

bers heightwise of the shoe each relatively to the other about an axis located nearer the end of the toe.

16. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to engage the inner face of the lip of the insole along the opposite sides of the toe respectively and also to engage the bottom of the insole adjacent to the lip, holders supporting said members and arranged to extend lengthwise of the shoe opposite the forepart of the shoe bottom, different pairs of bars arranged to extend heightwise of the shoe and pivotally connected respectively to the opposite end portions of said holders, means connected to the pair of bars located nearer the end of the toe for adjusting said holders in unison heightwise of the shoe about their pivotal connections with the other pair of bars, and means connected to said other pair of bars for adjusting the holders relatively to each other heightwise of the shoe about their connections with said first-named pair of bars.

17. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to extend lengthwise of the shoe in engagement with the inner face of the lip of the insole at the opposite sides of the toe respectively and also to engage the bottom of the insole adjacent to the lip, and means for adjusting the portions of said members located comparatively remote from the end of the toe relatively to each other heightwise of the shoe by swinging the members each about an axis located nearer the end of the toe and for retaining the members in their adjusted positions.

18. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to extend lengthwise of the shoe in engagement with the inner face of the lip of the insole at the opposite sides of the toe respectively and also to engage the bottom of the insole adjacent to the lip, and means for adjusting the portions of said members located comparatively remote from the end of the toe heightwise of the shoe by swinging the members each about an axis located nearer the end of the toe, said adjusting means comprising a lever connected to both members for thus adjusting them simultaneously in opposite directions.

19. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to extend lengthwise of the shoe in engagement with the inner face of the lip of the insole at the opposite sides of the toe respectively and also to engage the bottom of the insole ad-

ja cent to the lip, a lever connected to both said members for adjusting the portions thereof located comparatively remote from the end of the toe simultaneously in opposite directions heightwise of the shoe by swinging the members each about an axis located nearer the end of the toe, and adjustable stop mechanism for limiting movements of said lever in opposite directions to determine the relative adjustments of the members for right and left shoes respectively.

20. In a lasting machine, the combination with wipers for wiping the marginal portion of an upper about the toe end of a last inwardly over an insole on the last and against a lip on the insole, of means for positioning the shoe relatively to said wipers, said shoe-positioning means comprising a pair of shoe-positioning members arranged to extend lengthwise of the shoe in engagement with the inner face of the lip of the insole at the opposite sides of the toe respectively and also to engage the bottom of the insole adjacent to the lip, holders supporting said members and mounted to swing heightwise of the shoe each about an axis located comparatively near the end of the toe, a pair of bars arranged to extend heightwise of the shoe and pivotally connected respectively to said holders in locations farther from the end of the toe, a lever connected at its opposite ends respectively to said bars and mounted to swing about an axis extending lengthwise of the shoe to adjust said holders simultaneously in opposite directions respectively heightwise of the shoe, and means for determining opposite limits of movement of said lever for right and left shoes respectively.

21. In a lasting machine, the combination with toe-lasting means, of means for positioning a shoe relatively to said toe-lasting means, said shoe-positioning means comprising a pair of insole-engaging members arranged to extend lengthwise of the shoe along the bottom of the toe end of the shoe at the opposite sides of the toe respectively, the portions of said members located comparatively remote from the end of the toe being adjustable relatively to each other heightwise of the shoe by swinging the members each about an axis located nearer the end of the toe.

22. In a lasting machine, the combination with toe-lasting means, of means for positioning a shoe relatively to said toe-lasting means, said shoe-positioning means comprising a pair of insole-engaging members arranged to extend lengthwise of the shoe along the bottom of the toe end of the shoe at the opposite sides of the toe respectively, and means for adjusting the portions of said members located comparatively remote from the end of the toe relatively to each other heightwise of the shoe by swinging the members each about an axis located nearer the end of the toe, said adjusting means comprising a lever connected to both members for thus adjusting them simultaneously in opposite directions respectively.

23. In a lasting machine, the combination with toe-lasting means, of means for positioning shoes in proper relation to said toe-lasting means, said shoe-positioning means being adjustable for shoes of different styles, and means for properly locating a shoe of a given style in the machine to serve as a guide in the adjustment of said shoe-positioning means for shoes of that style.

24. In a lasting machine, the combination with

toe-lasting means, of means for positioning shoes in proper relation to said toe-lasting means, said shoe-positioning means being adjustable for shoes of different styles, and means movable prior to the operation of the machine on shoes of a given style into position to engage and properly locate such a shoe in the machine to serve as a guide in the adjustment of said shoe-positioning means for shoes of that style.

- 10 25. In a lasting machine, the combination with
wipers for wiping the marginal portion of an upper
about the toe end of a last inwardly over
an insole on the last, of means for positioning the
shoe relatively to said wipers by engagement with
the insole, said shoe-positioning means being ad-
justable for shoes of different styles, and means
for properly locating a last and insole of a given
style in the machine by engagement with the
insole to serve as a guide in the adjustment of
said shoe-positioning means for shoes of that
style.

15 26. In a lasting machine, the combination with
wipers for wiping the marginal portion of an upper
about the toe end of a last inwardly over
an insole on the last and against a lip on the
insole, of means for positioning the shoe rela-
tively to said wipers by engagement with the in-
ner face of the lip of the insole and with the
bottom of the insole adjacent to said lip, said
20 shoe-positioning means being adjustable for
shoes of different styles, and means for properly
locating a last and insole of a given style in the
machine by engagement with the feather of the
toe-end portion of the insole to serve as a guide
in the adjustment of said shoe-positioning means
for shoes of that style.

25 27. In a lasting machine, the combination with
wipers for wiping the marginal portion of an upper
about the toe end of a last inwardly over
an insole on the last and against a lip on the
insole, of means for positioning the shoe rela-
tively to said wipers by engagement with the in-
ner face of the lip of the insole and with the
bottom of the insole adjacent to said lip, said
30 shoe-positioning means being adjustable for
shoes of different styles, and means for properly
locating a last and insole of a given style in the
machine to serve as a guide in the adjustment of
said shoe-positioning means for shoes of that
style.

35 28. In a lasting machine, the combination with
wipers for wiping the marginal portion of an upper
about the toe end of a last inwardly over
an insole on the last and against a lip on the
insole, of means for positioning the shoe rela-
tively to said wipers by engagement with the in-
ner face of the lip of the insole and with the
bottom of the insole adjacent to said lip, said
40 shoe-positioning means being adjustable for
shoes of different styles, and means for properly
locating a last and insole of a given style in the
machine to serve as a guide in the adjustment of
said shoe-positioning means for shoes of that
style, said locating means comprising a plurality
45 of fingers arranged to extend heightwise of the
last with their end faces in engagement with the
feather of the insole at the opposite sides of the
toe.

50 29. In a lasting machine, the combination with
wipers for wiping the marginal portion of an upper
about the toe end of a last inwardly over
an insole on the last and against a lip on the
insole, of means for positioning the shoe rela-
tively to said wipers by engagement with the in-
ner face of the lip of the insole and with the
bottom of the insole adjacent to said lip, said
55 shoe-positioning means being adjustable for
shoes of different styles, and means for properly
locating a last and insole of a given style in the
machine to serve as a guide in the adjustment of
said shoe-positioning means for shoes of that
style, said locating means comprising members
60 arranged to engage the feather of the insole at
the opposite sides of the toe, and supports for
said members movable to carry them either into
position for use or into idle positions.

65 30. In a lasting machine, the combination with
wipers for wiping the marginal portion of an upper
about the toe end of a last inwardly over
an insole on the last and against a lip on the
insole, of means for positioning the shoe rela-
tively to said wipers by engagement with the in-
ner face of the lip of the insole and with the
bottom of the insole adjacent to said lip, said
70 shoe-positioning means being adjustable for
shoes of different styles, and means for properly
locating a last and insole of a given style in the
machine to serve as a guide in the adjustment of
said shoe-positioning means for shoes of that
style, said locating means comprising members
75 arranged to engage the feather of the insole at
the opposite sides of the toe, and supports for
said members movable to carry them either into
position for use or into idle positions.

PHILIP E. BURBY.
